UNITED STATES PATENT OFFICE

2,324,342

ANODE

Holley G. Wellman, East Cleveland, Ohio, assignor
to The Wellman Bronze and Aluminum Com-
pany, Cleveland, Ohio, a corporation of Ohio

Application January 8, 1941, Serial No. 373,202

2 Claims. (Cl. 204—238)

The invention relates to anodes for use in electroplating, and particularly to anodes adaptable for use in chromium electroplating.

The objects of the invention are to provide an anode which will not readily be broken or injured, the parts of which will not be adversely affected by the constituents of the electrolytic bath, the improved structure being particularly effective in preventing deleterious electrolytic action in localized areas; the improved anode being adapted to sustain an even and uniform wear in service, and being capable of economic manufacture and use and convenient application for use. Furthermore, the improved anode is very effective in use in that it provides a great number of throws or discharge lines for the current.

The invention is particularly an improvement in anodes of the character shown in U. S. Patent No. 2,109,975.

The annexed drawing and the following description set forth in detail certain means embodying the invention, such means constituting, however, but one of the various forms in which the principle of the invention may be embodied.

In said annexed drawing:

Figure 1 is a vertical section of a more or less conventional assembly of a treating tank, an electrolytic bath contained therein, and suitable electrical connections, for electroplating, in which the instant invention serves as the anode;

Figure 2 is a broken enlarged side view of the improved anode, the bus-bar from which the anode depends being shown in section;

Figure 3 is a rear view of the elements shown in Figure 2;

Figure 4 is a fragmentary enlarged longitudinal section, showing the upper part of the anode, this view particularly illustrating means for connecting the anode body to a hook by means of which the anode is dependably supported from a bus-bar; and

Figures 5 and 6 are transverse sections taken, respectively, in the planes indicated by the lines 5—5 and 6—6, Figure 4.

Referring particularly to the annexed drawing in which the same parts are indicated by the same respective numbers in the several views, the improved anode 1, preferably a cast member, is of the herring-bone type and, as used in practice, Figure 1, is suspended in a suitable electrolytic bath 3 which serves as the plating solution, being preferably a mixture of chromic and sulphuric acids for chromium plating, the bath 3 being contained in a suitable treatment tank 2 being lined with sheet lead. A proper level for the

plating solution is indicated by the gauge markings 17. The work 4 to be plated is suspended in the bath 3 by a hook 6 depending from a bus-bar 8 mounted upon a conductor 7, whereby the work 4 is connected in circuit with the negative pole of a source of electric current. The anodes 1 are dependably supported by bus-bars 8 suitably mounted upon the treatment tank 2 and which in turn support a conductor 9 whereby the anodes 1 are connected with the positive pole of the current source.

The improved anode 1 includes a herring-bone body 11 having a plurality of oppositely-disposed spaced laterally-extended fins 12. The body 11 and fins 12 are substantially flat plane members whose adjacent sides are substantially relatively right angular so that there are provided eight sharp edges 13 on each arm 12 and two sharp edges 14 on the body member 11 between adjacent arms 12, thus to provide the anode with a comparatively great number of electric throws or discharge lines, whereby the anode has great capacity. Also, such construction permits the use of a comparatively light anode compared to its capacity, and also provides even and uniform wear as the anode is consumed.

The upper end of the anode body 11 is enlarged, as indicated by the end portion 15, and is formed with a deep socket 16. However, the socket 16 does not extend completely to the bottom of the enlarged end portion 15 so that an enlarged strengthened section 17 of the body 11 is formed between the bottom of the socket 16 and the lower part of the anode body portion 11. This strengthened section 17 provides assurance against a break occurring in this portion of the anode by reason of its weight.

The anode 1 is dependably supported from the bus-bar 8 by an upper anode portion 18 consisting of a bar having an angular lower portion 19 and a hook-like upper end portion 20. The extreme lower end portion of the bar 18 is secured in the socket 16 of the enlarged upper anode body portion 15. Preferably, the enlarged anode portion 15 is cast around the lower portion of the bar 18, and a secure connection between these members is obtained by first roughing up the outer surface of the lower portion of the rod 18, as by providing notches 23, Figures 4 and 6, in which key-like masses 15' of the enlarged portion 15 are formed during the casting operation.

The anode body 11 consists of an alloy, of which the preponderant portion is lead. The supporting bars 18 are preferably formed of copper which, for protection against acids and acid

radicals, particularly at the level of the depositing solution, is preferably faced with a coating of tin and lead.

Lead and copper occasion an electrolytic action which weakens the supporting bar 18, particularly at the joint between this bar 18 and the supported anode body 11. Oftentimes there are small pockets at this joint and, in any event, seepage creates small pockets, and in these pockets the deleterious action proceeds which weakens the supporting bar 18. The solution maintaining this deleterious action obtains access to these pockets, largely by reason of solution drip occasioned by the manipulation of the various elements during the electroplating procedure.

To obviate the creation of these pockets, and the penetration thereof by the solution, and, hence, the deleterious electrolytic action mentioned, the angular portion 19 of the supporting rod 18 is provided with a collar 21, preferably cast integrally with the supporting rod 18. This collar 21 overhangs the upper end portion of the enlarged anode portion 15 and is so located as to contact with its lower face said upper end portion, when the extreme lower portion of the rod 18 is properly seated in the socket 16. After the casting of the enlarged anode portion 15 about the lower end of the supporting rod 18, the upper peripheral edge portion 22 of the enlarged anode portion 15 is peened against the lower face of the collar 21 to the extent necessary to take up any recess between the collar 21 and the anode portion 15 created during the casting operation, and the joint is then filled or covered with lead. Thus, the collar 21 acts as a watershed for the drip of the depositing solution and diverts the same back into the bath 3 without its being permitted to seep into or otherwise enter the joint between the enlarged anode portion 15 and the supporting rod 18.

What I claim is:

1. An anode for electroplating comprising a supporting member and a body member depend-

ing therefrom, said members being comprised of different alloys and having cooperating portions secured together and forming a joint therebetween, the alloys of which the members are comprised being such as, in combination with the plating bath, to maintain deleterious electrolytic action at the joint tending to weaken the supporting member, and means for preventing plating bath drip from above the joint contacting the latter consisting of an imperforate collar surrounding said joint and overhanging the body member at the joint, said collar having a downwardly sloped upper surface whose drip edge is extended throughout its periphery exteriorly of and free from contact with the portions of said members forming said joint, and said collar inwardly of its drip edge having sealing engagement in an unbroken and endless band with said supporting and body members.

2. An anode for electroplating comprising a supporting member having a depending end portion formed with an imperforate outwardly extended collar having a downwardly sloped upper surface, and a body member formed with an upper end socket within which said depending end portion is seated with the lower face of the collar in sealing engagement in an unbroken and endless band with the upper end face of the body member to form a joint between said members 25 interiorly of the drip edge of the upper surface of the collar, the supporting and body members being comprised of different alloys such as, in combination with the plating bath, to maintain deleterious electrolytic action at the joint tending to weaken the supporting member, said collar surrounding the joint and overhanging the body member at the joint, and said drip edge being extended entirely exteriorly of said upper end face of the body member, whereby plating bath 30 drip from above the joint is prevented from contacting the latter.

HOLLEY G. WELLMAN.
